(57) **CLAIM**

The ornamental design for a gaiter with stirrup, as shown and described.

DESCRIPTION

FIG. 1 is a first perspective view of a gaiter with stirrup showing the new design.

FIG. 2 is a top view of the gaiter with stirrup of FIG. 1 showing the new design.

FIG. 3 is a bottom view of the gaiter with stirrup of FIG. 1 showing the new design.

FIG. 4 is a front view of the gaiter with stirrup of FIG. 1 showing the new design.

FIG. 5 is a rear view of the gaiter with stirrup of FIG. 1 showing the new design.

FIG. 6 is a first side view of the gaiter with stirrup of FIG. 1 showing the new design.

FIG. 7 is a second side view of the gaiter with stirrup of FIG. 1 showing the new design.

FIG. 8 is a plan view of the inside of the gaiter with stirrup of FIG. 1 showing the gaiter in a fully open position; and, FIG. 9 is a plan view of the outside of the gaiter with stirrup of FIG. 1 showing the gaiter in a fully open position.

FIGS. 1-7 show the invention being worn by a person. FIGS. 8-9 show the invention when it is not being worn by a person. The broken lines are to show environmental structure only and form no part of the claimed design.

1 Claim, 6 Drawing Sheets
